CLAIM

The ornamental design for a wood splitter, as shown and described.

DESCRIPTION

FIG. 1 is a front elevation view of a wood splitter showing my new design;

FIG. 2 is a rear elevation view thereof;

FIG. 3 is a left side elevation view thereof;

FIG. 4 is an enlarged detail view of the area indicated in FIG. 3;

FIG. 5 is a right side elevation view of FIG. 1;

FIG. 6 is a top plan view thereof;

FIG. 7 is a bottom plan view thereof;

FIG. 8 is a top right rear perspective view thereof;

FIG. 9 is a top right front perspective view thereof;

FIG. 10 is a front elevation view of a wood splitter showing a second embodiment of my new design;

FIG. 11 is a rear elevation view thereof;

FIG. 12 is a left side elevation view thereof;

FIG. 13 is a right side elevation view thereof;

FIG. 14 is an enlarged detail view of the area indicated in FIG. 13;

FIG. 15 is a top plan view of FIG. 10;

FIG. 16 is a bottom plan view thereof;

FIG. 17 is a top left rear perspective view thereof; and,

FIG. 18 is a top left front perspective view thereof.

The broken lines in the figures depict portions of the article which form no part of the claimed design.
